United States Patent Office

Des. 228,360
Patented Sept. 11, 1973

228,360

HANGABLE TERRARIUM

Richard B. Sunshine, 7118 Greenville Ave.,
Dallas, Tex. 75231

Filed June 7, 1972, Ser. No. 260,712

Term of patent 14 years

Int. Cl. D11—02; D30—02

U.S. Cl. D35—3 A

FIG. 1 is an isometric view of the terrarium showing my design;

FIG. 2 is a top plan view of the same with the portion of the hanging cords cut away;

FIG. 3 is a side elevation with a portion of the cords cut away for ease of illustration;

FIG. 4 is a bottom plan view of the same.

I claim:

The new and ornamental design for a hangable terrarium, substantially as shown and described.
